ATTORNEY

UNITED STATES PATENT OFFICE.

JOHN JACKSON, OF BROOKLYN, NEW YORK, ASSIGNOR TO AMERICAN MACHINE & FOUNDRY COMPANY, A CORPORATION OF NEW JERSEY.

DUPLEX ROTARY PUMP.

Application filed October 9, 1924. Serial No. 742,526.

To all whom it may concern:

Be it known that I, JOHN JACKSON, a subject of the King of England, residing at Brooklyn, county of Kings, and State of New York, have invented a new and useful Improvement in Duplex Rotary Pumps, of which the following is a specification.

This invention relates to a duplex rotary pump of the high speed type adapted to be driven by direct connection with an electric motor, although it may be otherwise driven if desired. The main object of the invention is the production of a pump of this type, in which the rotating parts are perfectly balanced, and in which wear is reduced to a minimum, both features contributing to high efficiency. A further object of the invention is the production of a pump of this kind, the rotating parts of which may be run in either direction. With these and other objects not specifically mentioned in view, the invention consists of certain constructions and combinations which will be hereinafter fully described and then specifically set forth in the claims hereunto appended.

In the accompanying drawings, which form a part of this specification and in which like characters of reference indicate the same or like parts, Fig. 1 is a central sectional elevation of a pump constructed in accordance with the invention; Fig. 2 is a cross-sectional view of the pump shown in Fig. 1; and Fig. 3 is a diagrammatic view showing the development of the inlet and outlet ports and the rotor of the pump shown in Figs. 1 and 2.

In carrying the invention into effect, there is provided a cylinder having inlet and outlet ports, means for dividing the interior of said cylinder into a plurality of annular chambers, axially movable means for segregating the ports to prevent leakage from an inlet port to an outlet port—or vice versa—at any point in the operation of the device, a rotor operative in said chambers in peripheral contact with the inner perimeter of the cylinder and having helical faces engaging and operating said segregating means, and means for operating the rotor. All of the above mentioned parts and means may be widely varied in construction within the scope of the claims, for the particular device selected to illustrate the invention is but one of many possible concrete embodiments of the same.

The invention therefore is not to be restricted to the precise details of the structure shown and described.

Referring to the drawings, 4 indicates a cylinder bored in a casting 5 and provided with heads 6 and 7 bolted to the cylinder proper. Each of the heads supports a bearing bush 8, and the head 6 supports a gland 9 and packing 10 of well known construction and operation. Mounted in the bearings 8 is a drive shaft 11 which may be directly driven by an electric motor, or by any other suitable means.

Means are provided for dividing the interior of the cylinder 4 into a plurality of annular chambers 12, there being three of these chambers in the pump illustrated. As shown, this dividing means consists of two annular members 13 stationarily held in the cylinder by means of bolts 14 threaded in the cylinder walls and engaging suitable apertures in the peripheries of said members.

The cylinder 4 is provided with a series of inlet ports 15 and with a series of outlet ports 16, these ports being cut through the cylinder wall at its bottom.

For the purpose of preventing leakage of pumped fluid from one set of ports to the other at any time, there is provided axially movable means for segregating said ports; and as shown, this means includes two vanes 17, each slidably positioned in a slot in the perimeter of one of the stationary annular members 13 before referred to. The vanes engage the inner perimeter of the cylinder between the inlet port 15 and the outlet port 16. These vanes are so mounted that they may have an axial sliding movement always in contact with the inner perimeter of the cylinder, but they have no rotating movement.

There is further provided a rotor which, as shown, is made up of parts rotatable in the chambers 12 in peripheral contact with the inner perimeter of the cylinder 4, and these parts are collectively in perfect balance. As shown, the rotor is made up of three parts 18, 19 and 20, the part 18 having oppositely disposed helical faces 21, and the parts 19 and 20 each having one helical face 21. The rotor parts 18, 19 and 20 are all mounted on the drive shaft 11 before referred to, and are keyed thereto by means of a long key 22. Spacers 23 surround the

shaft 11 between the rotor parts, and these spacers also are keyed to the shaft 11 by means of the long key 22. The parts of the rotor are held together by means of a series 5 of four bolts 24, each having a nut 25 at each of its ends. The helical faces 21 of the rotor parts 18, 19 and 20 engage the ends of the vanes 17, and as the rotor turns, the vanes are moved axially in the slots of the 10 stationary members 13 to always segregate the inlet and outlet ports and force the pumped fluid drawn from the inlet ports into the chambers 12 out through the outlet ports. By an inspection of Fig. 3, it will 15 be seen that the movements of the vanes are always in opposite directions, so that even these light parts operate in perfect balance. The middle part 18 of the rotor serves to divide the middle chamber 12 into two parts, 20 so that although the dividing members 13 divide the cylinder into three chambers, there are really four chambers because the middle one is divided into two parts by the middle part of the rotor, and as a result of 25 this construction, the end-thrust in both directions is in perfect balance and no undue wear of the stationary and movable parts will occur.

Means are provided for draining the cylinder of any fluid which may leak past the rotor, and as shown, the drainage is into one 30 of the inlet ports 15 and is effected by means of a main pipe 26 connecting one end of the cylinder with one of the inlet ports 15, and by a branch pipe 27 connecting the opposite end of the cylinder with the pipe 26. This pipe arrangement is reversible so that if the pump is to be operated in the 35 opposite direction, the inlet ports 15 would become outlet ports; the outlet ports 16 would become inlet ports; and the pipe 26 would be connected with one of the ports 40 now numbered 16, which would then be an inlet port.

Each of the inlet and outlet ports is so 45 located that one of the rotor parts completely closes it when its periphery at its widest part passes over it. Thus, in Fig. 3, the inlet and outlet ports controlled by the 50 rotor parts 19 and 20 are both closed; while the inlet ports 15 and outlet ports 16 controlled by the rotor part 18 are both open; so that when the parts are in the position shown in this figure, the chamber in which 55 the rotor parts 19 and 20 move are completely out of operation, but the chambers controlled by the rotor part 18 are in full operation. It will be understood that as the 60 rotor turns from the position shown in Fig. 3 and the middle ports begin to close, the outer ports will begin to open. As a result of this construction, there is always a substantially constant open port area and consequently a substantially constant flow of 65 fluid through the pump.

What is claimed is:

1. A pump comprising a cylinder having inlet and outlet ports, means for dividing the interior of said cylinder into a plurality of annular chambers, axially movable means 70 for segregating said ports, a rotor operative in said chambers in peripheral contact with the inner perimeter of said cylinder and having helical faces operating said segregating means and made up of a member 75 for each chamber, spacers separating said members, and through bolts holding said members and spacers together, and means for operating said rotor.

2. A pump comprising a cylinder having 80 inlet and outlet ports, means for dividing the interior of said cylinder into a plurality of annular chambers, axially movable means for segregating said ports, a rotor operative in said chambers in peripheral contact 85 with the inner perimeter of said cylinder and having helical faces operating said segregating means and made up of a member for each chamber, spacers separating said members, and through bolts holding said 90 members and spacers together, and means for operating said rotor, said dividing means including a plurality of stationary annular members having slots in their perimeters for positioning said segregating 95 means.

3. A pump comprising a cylinder having 100 inlet and outlet ports, means for dividing the interior of said cylinder into a plurality of annular chambers, axially movable means for segregating said ports, a rotor operative in said chambers in peripheral contact with the inner perimeter of said cylinder and having helical faces operating 105 said segregating means and made up of a member for each chamber, spacers separating said members, and through bolts holding said members and spacers together, and means for operating said rotor, said dividing means including a plurality of annular members bolted to said cylinder and having slots in their perimeters for positioning 110 said segregating means.

4. A pump comprising a cylinder having 115 inlet and outlet ports, means for dividing the interior of said cylinder into a plurality of annular chambers, axially movable means for segregating said ports, a rotor operative in said chambers in peripheral contact with the inner perimeter of said cylinder and having helical faces operating 120 said segregating means and made up of a member for each chamber, spacers separating said members, and through bolts holding said members and spacers together, and means for operating said rotor, said segregating means including vanes axially 125 slid able on the inner perimeter of said cylinder between said ports.

5. A pump comprising a cylinder having 130

- inlet and outlet ports, means for dividing the interior of said cylinder into a plurality of annular chambers, axially movable means for segregating said ports, a rotor operative in said chambers in peripheral contact with the inner perimeter of said cylinder and having helical faces operating said segregating means and made up of a member for each chamber, spacers separating said members, and through bolts holding said members and spacers together, and means for operating said rotor, and pipes for draining into said inlet port any fluid leaking past said rotor. 5
10. A pump comprising a cylinder having inlet and outlet ports, means for dividing the interior of said cylinder into a plurality of annular chambers, axially movable means for segregating said ports, a rotor operative in said chambers in peripheral contact with the inner perimeter of said cylinder and having helical faces operating 75 said segregating means and made up of a member for each chamber, spacers separating said members, and through bolts holding said members and spacers together, and means for operating said rotor, and pipes for draining into said inlet port any fluid leaking past said rotor. 10
15. The inner perimeter of said cylinder and between said ports. 15
6. A pump comprising a cylinder having inlet and outlet ports, means for dividing the interior of said cylinder into a plurality of annular chambers, axially movable 20 means for segregating said ports, a rotor operative in said chambers in peripheral contact with the inner perimeter of said cylinder and having helical faces operating 80 said segregating means and made up of a member for each chamber, spacers separating said members, and through bolts holding said members and spacers together, and means for operating said rotor, said inlet and outlet ports being so located that the 85 rotor completely closes them when its periphery at its widest part passes over them. 90
25. 7. A pump comprising a cylinder having inlet and outlet ports, means for dividing the interior of said cylinder into a plurality of annular chambers, axially movable 95 means for segregating said ports, a rotor operative in said chambers in peripheral contact with the inner perimeter of said cylinder and having helical faces operating said 100 segregating means and made up of a member for each chamber, spacers separating said members, and through bolts holding said members and spacers together, and means for operating said rotor, said cylinder being provided with a set of four inlet ports and a set of four outlet ports, and said 105 rotor being so mounted that two inlet ports and two outlet ports are completely closed when the other two inlet ports and the other 110 two outlet ports are wide open. 40
45. 8. A pump comprising a cylinder having inlet and outlet ports, means for dividing the interior of said cylinder into a plurality of annular chambers, axially movable 50 means for segregating said ports, a rotor operative in said chambers in peripheral contact with the inner perimeter of said cylinder and having helical faces operating 115 said segregating means and made up of a member for each chamber, spacers separating said members, and through bolts holding said members and spacers together, and means for operating said rotor, and means for draining into said inlet port any fluid 120 leaking past said rotor. 55
55. 9. A pump comprising a cylinder having inlet and outlet ports, means for dividing the interior of said cylinder into a plurality of annular chambers, axially movable 60 means for segregating said ports, a rotor operative in said chambers in peripheral contact with the inner perimeter of said cylinder and having helical faces operating 125 said segregating means and made up of a member for each chamber, spacers separating said members, and through bolts holding said members and spacers together, and means for operating said rotor, four of said chambers being provided to balance the rotor and prevent end-thrust thereof in said cylinder. 65

In testimony whereof, I have signed my name to this specification.

JOHN JACKSON.
